UNITED STATES PATENT OFFICE.

ALEXANDER McGARY, OF LA GRANGE, ILLINOIS, ASSIGNOR OF ONE-FIFTH TO
CHARLES GILBERT HAWLEY, OF CHICAGO, ILLINOIS.

AXLE LIGHTING SYSTEM.

No. 906,055.

Specification of Letters Patent.

Patented Dec. 8, 1908.

Application filed August 11, 1905. Serial No. 273,822.

To all whom it may concern:

Be it known that I, ALEXANDER McGARY, a citizen of the United States, and a resident of La Grange, Cook county, Illinois, have invented a certain new, useful, and Improved Axle Lighting System, of which the following is a specification.

My invention relates to the lighting of railroad trains by electricity and has particular reference to improvements in electric lighting systems of that class known as axle lighting-systems and characterized by a storage battery and by a generator that is driven by the car axle. The practice hitherto generally followed in devising and operating said systems has involved the use of current and voltage regulators, and the maintenance of a constant current upon the lighting or lamp circuit of the system. My investigations and experiments show that such axle lighting systems are needlessly complicated and that the complication is chiefly attributable to the efforts made to regulate the current output and keep the same constant. In my invention I proceed upon the basis of the known fact that the lamps or other translating devices belonging to such a system will themselves determine the current consumption and in contra-distinction to the known systems my novel system is characterized by the maintenance of a constant voltage upon the lamp or working circuit of the system, without regard to the varying current flow.

The object of my invention may be briefly stated as being to provide an electric lighting system which shall include a dynamo to be driven from a car axle, and a storage battery together with means that shall adapt the same to supply electric current, adequate to the varying demands of the lamp circuit, at a constant voltage.

Another object of my invention is to provide an electric system of the class mentioned which, when in operation shall, automatically charge the storage battery in a manner most favorable to its longevity.

A further object of the invention is to simplify the construction and circuits of electric lighting systems for railroad cars with a view to reducing the initial and maintenance costs connected therewith.

Other objects of my invention will appear hereinafter.

My invention consists generally in a sys-

tem of electric generation and distribution comprising a lamp circuit, a duplex generator, a storage battery, and an automatic switch or circuit closer, adapted to connect the battery alone in the lamp circuit, and also adapted to disconnect the battery from the lamp circuit and connect one of the windings of the duplex generator with the battery and at the same time connect the other winding of the generator with the lamp circuit; and further, my invention consists in an electric system further characterized by automatic voltage regulating and pole-changing apparatus, the same comprising an auxiliary electric generator or exciter having its field variably energized from a suitable source such as the lamp circuit and having its armature driven by or with the armature of the duplex generator and arranged to energize the field thereof; and my invention consists further in various details of construction, in circuits and in circuit relations; all as hereinafter described and particularly pointed out in the claims.

My invention will be more readily understood by reference to the accompanying drawings, forming a part of this specification and in which;

Figure 1, is a diagrammatic view of an electric system embodying my invention, the switches thereof being shown in the positions assumed when the storage battery is alone furnishing current to the lamp circuit, the generators being assumed to be at rest or with their armatures in slow rotation; Fig. 2 is a similar diagrammatic view, showing only those members and circuits which are energized when the dynamos are at rest and the battery is supplying the lamp circuit with energy. Fig. 3 is another diagrammatic view, showing the members and circuits which are energized when the dynamos are in operation; Fig. 4 is an enlarged detail view of the resistance varying means and the circuit closer employed in my system; and Fig. 5 is like unto Fig. 4 but shows the circuit closer closed.

As shown in the drawings, A, represents a group of electric lamps, and B, the lamp circuit, whereof B¹ and B² are the terminals.

C, is a duplex generator, having a single armature provided with two windings or sets of coils, D and E. These are wound upon a single core and hence rotate together. The armature winding, D, as hereinafter ex-

plained, supplies energy to the lamp circuit. The winding E contains a greater number of turns than winding D and supplies energy to the storage battery at voltage greater than that on the lamp circuit.

F, represents the field windings of the duplex generator, wound upon a single set of poles.

The armature shaft, G, is driven from the car axle, H, a belt or other suitable transmission being employed to connect the shafts as indicated. A small, auxiliary generator or exciter is arranged on the same shaft, that is its armature I, is fixed upon the main armature shaft, G. Hence, the armatures of the main and auxiliary generators revolve, always, at the same speed and in the same direction. The terminals of the armature I, are connected to the terminals of the main field winding F, by lines I¹ and I². Hence when the shaft G is rotated the main generator will be energized or excited by current from the auxiliary generator. The field winding J, of the auxiliary generator is connected across the terminals of the lamp circuit, B, or other portion of the system which is constantly energized during operation. This connection includes the variable resistance J¹, and is traced through the lines, J², J³, J⁴ and the line K. The latter being the common return line or connection of the system. The office of the resistance is to vary the intensity of current in the auxiliary field and thus vary the output of the auxiliary armature, and hence the strength of the main field. It is in this manner that I regulate the output of the main generator, and it will be seen that said output will depend upon the speed with which the main armature is rotated and the strength of the main field. Speaking generally, the operation of the auxiliary generator is to weaken the main field as the main armature speed is increased.

L, represents a suitable storage battery, one terminal of which is connected with the line, K, and thereby to the lamp circuit terminal, B².

M, represents a hot wire or ribbon, this being an expansible conductor that is arranged in circuit across the poles or terminals of the lamp armature winding, D, as shown by lines, M¹ and M². One end of the hot wire, M, is secured to a stationary support, and the other end, by means hereinafter described, is attached to the compression lever, N, belonging to the compression resistance, J¹. The lever, N, carries a contact, O, which is insulated therefrom, and is adapted to engage the lever, O¹; these parts constituting a circuit closer for the circuit of the automatic switch.

O² is a limiting stop for the lever, O¹, and the contact, O, only engages the lever, O¹, when and after the hot wire, M, has been expanded by a flow of current therethrough.

P, represents the lever of the automatic switch, and P¹, is the electro-magnet which is adapted to move said lever, P, against the tension of a retractile spring, P². The position of the automatic switch, P, determines the operating condition of the system. In one position, the switch operates to place the battery in the lamp circuit and in the other position, it operates to remove the battery from the lamp circuit and place it in the circuit of the duplex-armature winding, E, and at the same time, the switch places the armature winding, D, in the lamp circuit. In other words, the movement of the switch lever, P, by the electro-magnet, P¹, serves to replace the battery by the dynamo. The means and the manner in which this is accomplished will now be described.

The lever, P, is provided with a contact plate or bridge, P³, adapted to engage contacts L¹ and L². The contact, L¹ is connected with the battery by a line, L³, and the contact, L², with the lamp terminal, B¹, by line L⁴. When the lever is in position shown in Figs. 1 and 2, current will flow from the battery, L through line, L³, contacts, L¹, P³, and L², and thence through line L⁴, to the lamp circuit, B, returning to the battery through the terminal, B², and the line, K. At such times, the lamps will be supplied with current from the battery and therefrom only. On the opposite side of the lever, P, are plates, P⁴ and P⁵. When the lever, P, is drawn down by magnet, P¹, these plates, P⁵, and P⁴ engage respectively, the pairs of contacts, D¹, D² and E¹, E². These last represent the duplex armature windings, D and E respectively. When P⁵ rests upon the contact D¹, D², the armature D is connected to the terminals of the lamp circuit. The circuit at such time may be traced from the lamp terminal, B², through line, D³, through the armature, D, then the line, D⁴ and through contacts D¹, P⁵, D², and line, D⁵ to the lamp circuit terminal, B¹, completing the circuit, B, which includes the lamps, A.

The electro-magnet, P¹, is connected with the lamp armature line D⁴ by line, D⁶, and its opposite terminal is connected with the switch lever, O¹, through line, O³, the magnet being bridged or connected across the terminals or poles of the armature, D, and the magnet, P¹, may be energized irrespective of the closing of the main circuit of said armature through contact, D¹, D². The magnet is therefore always in readiness to operate the switch lever, P, and the magnet is so proportioned that it will overcome the tension of the spring, P², and draw down the lever, P, to cut out the battery and put the armature, D, into the lamp circuit as soon as the main armature has attained sufficient speed to produce the current and voltage required by the lamps. This operation of the magnet P¹, however, does not take place immediately

upon the starting of the car and generator or at an indeterminate time, for the reason that the circuit is not closed through the magnet, P^1 , until the flow of current from armature D has caused sufficient expansion of the hot wire, M , to permit the contact, O , to engage the switch lever, O^1 . The hot wire, therefore, is the means employed for controlling or determining the action of the automatic switch, and said wire is so proportioned that its sufficient expansion will occur only when the armature, D , has reached the minimum speed that will enable it to supply current at the requisite voltage.

15 The operation of the automatic switch with relation to the armature, E , is as follows: The negative terminal of the armature winding, E , is connected with the battery, L , by the lines E^3 and K . The positive terminal of the winding E , is connected to the switch contact E^1 , by the line E^4 . The contact, E^2 , is connected by a short line E^5 to the battery line, L^3 . When the bridge, P^4 , closes upon the contact, E^1 and E^2 , the battery will be cut off the lamp circuit and connected with the armature winding, E , to be charged therefrom. The flow of current at that time will be from the positive terminal of armature, E , through line E^4 , contacts E^1 , P^4 and E^2 , and line E^5 to the battery L , returning from thence to the armature through lines K and E^3 . For the purpose of tapering the battery charge I introduce resistance ER in the line E^4 . The effective resistance or ER varies with the current flow. Consequently when the potential of the battery is low it will be charged at a high rate but by a current of relatively low voltage and as the capacity of the battery is approximated the voltage of the charging current will be increased, thereby insuring the completeness of the charge and protecting the battery from injury. The special merit of this portion of my apparatus is that its operation and regulation are wholly automatic.

It has been pointed out that the field of the exciter or auxiliary generator is supplied with a varying current and that the output of the main machine is controlled through this medium, and it now remains to be seen how the variation in the auxiliary field is effected. The hot wire or band, M , effects a variation of current in the field, J , of the auxiliary generator, by increasing or decreasing the pressure upon the carbon or other compression resistance, J , in proportion to the potential of the current upon the hot wire. Furthermore the hot wire causes the operation of the automatic switch, P , by opening and closing the switch, O , O^1 , in the circuit of the magnet, P^1 . The construction of the controlling device as a whole is shown in detail in Figs. 4 and 5, wherein it will be seen that a spring, ON , connects the levers, N , and O^1 , tending to draw them together, and another and weaker spring, O^5 , tends to draw the lever, O^1 , away from the stop, O^2 . The lever, N , presses upon the carbon disks, J^1 , and carries a spring case, N^1 . Within the case, N^1 , is a rod, N^2 , and plunger, N^3 . The rod works freely through an opening in the end of the casing, N^1 , and is attached to the free end of the hot wire, M . A spring, N^4 , between the plunger, N^3 , and the end of the casing, N^1 , tends to draw the lever, N , away from the lever, O^1 ; that is the plunger is fixed except as it is moved by the expansion and contraction of the hot wire; and the spring, acting from the stationary plunger, forces the lever toward the hot wire and hence away from the lever, O^1 , and against the resistance. Said resistance is composed, preferably, of a number of carbon disks or blocks and it will be obvious that when the wire or band is cold the spring will cause the lever to press heavily against the said disks. In this condition the device presents its minimum resistance to the flow of current through the auxiliary field, and the output of the auxiliary machine, if in rotation, will be the maximum. Thus the excitation or energization of the main generator is insured and made efficient from the start.

Obviously, as the hot wire is in circuit connection with the lamp armature, D , said wire will receive current from the time that the armature begins its rotation, and as the speed of the armature increases its greater output will cause an increase of pressure on the hot wire, with accompanying heat and consequent expansion. The early state of the controller is as shown in Fig. 4, and there is an adjustable nut or button, N^5 , on the threaded plunger rod, N^2 . When the hot wire, M , is expanded the spring, N^4 , will take up the expansion or slack of the wire, M , until the nut, N^5 , seats itself on the end of the casing on lever, N ; the spring meantime maintaining pressure on the compression resistance. The nut, N^5 , is so positioned that it will engage the lever, N , when the voltage upon the hot wire, due to the full energization of the main field and the more rapid rotation of the main armature, has closely approached the number of volts required upon the lamp circuit; and a slight increase on the hot wire circuit (thereafter operating to further expand said wire M) will cause the release of the lever, N , and permit the contact, O , to close upon the lever, O^1 . This action closes the circuit or shunt containing the magnet, P^1 and the operation of the switch follows immediately, the effect being to cut out the battery and place the main armature, D , in the lamp circuit. At the same time, the armature, E , is connected with the battery and will begin to recharge the same.

Reverting to the controller; it has been seen that the spring exerts its maximum

pressure upon the resistance, J^1 , when the wire, M , is cold and it will be evident that as the hot wire expands and thus lessens the spring pressure the effective resistance of the mass, J^1 , will be increased. In other words the field of the auxiliary generator will, because of the greater resistance in its circuit, be weakened and this will in turn result in weakening the field of the main generator and reduce the output of the lamp armature. In this measure the temperature of the hot wire will be reduced and the same will tend to reduce the resistance, J^1 , and cause the restoration of the armature output. This operation so far as it concerns the reduction of the output of the main generator does not begin to have practical effect until the lamp armature has been placed in the lamp circuit. It will now be understood that the further movement of the lever, N , which occurs after the switch, O , O^1 closes, is slight but is sufficient to vary the resistance, J^1 , to such extent as to cause the auxiliary generator to vary in response to slight fluctuations on the hot wire, M , and thus compensate for changes in the speed of the main generator armature and in the load on the lamp circuit. The result is a substantially constant voltage upon the lamp circuit which constant voltage is maintained irrespective of the current consumption and irrespective of variations of car speed, so long as the generator speed does not fall below the minimum. When a drop in speed does occur the hot wire which is in direct connection with the lamp circuit will at once respond and its contraction will result in opening the automatic switch circuit, whereupon the storage battery will be instantly restored to the lamp circuit and will remain therein until the generator speed again rises to the point at which the controller and switch operate to again close the circuits of the lamp and charging armatures. In practice suitable circuit closers are provided in the various circuits for the purpose of cutting off the lamps when desired and to prevent battery leakage, when the system is at rest, but such switches and the manner of their use being well known it has been deemed unnecessary to either show or describe them herein.

It being assumed that the system is in use, the operation of my invention is as follows: When the car that is equipped with my system is at rest, and also after the car has been started, but before the generator speed has reached the required minimum, the energized portions and circuits of the system are as shown in Fig. 2. At this time the battery is in circuit with the lamps, the upper contacts of the automatic switch serving to close the circuit through lamps and battery. During this period the field of the auxiliary generator is energized the degree of energization being the maximum inasmuch as said

auxiliary field, J , is in circuit across the poles of the battery and the strongly compressed resistance, J^1 , offers minimum obstruction to the passage of current through the field windings. The armature shaft being started 70 the hot wire which is in closed circuit with the armature winding, D , will be heated. Meantime the armature winding, E , remains idle as its circuit is open at the contacts E^1 and E^2 . As the speed of the armature increases the energization of the main field from the auxiliary armature also increases and the pressure increment upon the circuit of the hot wire, M , will cause further expansion thereof. This condition will continue 80 until the hot wire has been sufficiently expanded to permit the closing of the switch, O , O^1 , and the circuit of the automatic switch magnet, P^1 . Incidentally the effective resistance of J^1 , is slightly increased and consequently the auxiliary field, J , is weakened preparatory to the regulation of the main generator. When the magnet, P^1 , is energized and attains sufficient strength to close the automatic switch upon the contacts beneath it, the active members and circuits will be as shown in Fig. 3. The dotted lines in this figure show how the battery is cut out of the lamp circuit. The lamp circuit will now be supplied with energy from the armature winding, D , and the current flow in the battery will be reversed, the same being charged with current from the armature winding, E ; the resistance ER in that circuit operating in the advantageous manner 90 hereinbefore set forth. The hot wire, M , responds to every change of potential upon the lamp armature and in so doing causes the described variations of resistance in the circuit of the auxiliary field, J , thereby accomplishing the described variation of strength 100 in the field of the main generator which latter accurately compensates for every change in the speed of the armature shaft. The auxiliary generator is an automatic pole 110 changer for the main generator, that is, the polarity of the auxiliary field is constant by reason of the fact that the direction of the current in its winding is always the same and therefore when the armature shaft is rotated 115 oppositely the polarity of the auxiliary armature will reverse, thereby reversing the poles of the main generator field, to maintain the polarity of the lamp circuit and also the battery circuit.

As various modifications of my invention will readily suggest themselves to one skilled in the art I do not confine my invention to the specific constructions, relations and circuits herein shown and described.

Having thus described my invention, I claim as new and desire to secure by Letters Patent:

1. An electric system, comprising a working circuit containing electric translating de- 130

- vices, in combination with a storage battery, a direct current generator having a variably driven duplex direct current armature, one part of which is devoted to said working circuit, and the other to said battery, means for maintaining the voltage of said generator substantially constant at and above a certain speed of said armature, and means automatically operative to connect the respective parts of said armature to said circuit and said battery, when the minimum voltage speed of said armature is attained, and reversely operating to disconnect the same and connect the battery with said working circuit only, when the speed of said armature falls below the minimum, substantially as described.
2. In a system of electric generation and distribution a working circuit, in combination with a storage battery, a generator having a direct current duplex armature, means connecting said battery with said circuit, means for disconnecting the battery therefrom and connecting one of the windings of said armature with said lamp circuit, means for connecting the other armature winding with said battery, all said means working together as a unit, and suitable means for varying the strength of the field of said generator to maintain the voltage of said armature windings, substantially as described.
3. An electric system comprising, a storage battery, in combination with a direct current generator having a duplex armature, means for variably driving said armature, an auxiliary generator having its armature rotated in time with said duplex armature and arranged to energize the field of said generator, a working circuit connected with one of the windings of said duplex armature, a storage battery connected with the other winding of said armature, means whereby the field of said auxiliary generator is variably energized, causing variations in the fields of the main generator and means for disconnecting said working circuit and battery from respective windings and connecting said circuit and battery, substantially as described.
4. An electric system comprising a storage battery, in combination with a dynamo having a direct current duplex armature, a working circuit supplied from said battery or from one of the windings of said armature, a suitable switch for connecting one or the other with said circuit, said switch being adapted to connect the other winding of said armature to said battery when the latter is disconnected from the working circuit, switch operating means controlled by the voltage upon one of the windings of said armature and means whereby variations of voltage upon the working circuit following its connection with said armature are made to cause inverse variations in the field of said dynamo, substantially as described.
5. An electric system comprising a working circuit in combination with a storage battery, for occasional connection to said working circuit, two direct current main generator armatures, connected to said working circuit and battery respectively, common means for driving said armatures, a single suitably wound main generator field, an auxiliary generator having its armature driven with said main armatures and adapted to energize said main field, the field of said auxiliary generator being arranged in circuit across the poles of one of the main armatures, resistance in the circuit of the auxiliary field, and means automatically responsive to variations of potential upon said main armature and adapted to vary the resistance in the circuit of the auxiliary field, substantially as described.
6. An electric system comprising a working circuit, in combination with a storage battery, a generator having two direct current armatures in one body, one connected with said working circuit and the other connected in circuit with said battery and a charge controlling resistance, the latter armature winding being of a greater number of turns than the former, an auxiliary generator having its armature arranged to energize the field of the main generator and having its own field arranged in circuit across the poles of one of the main armatures, means automatically responsive to variations of potential upon said main armature for varying the strength of the auxiliary field, and a switch also responsive to variations of armature potential for placing said storage battery in the working circuit, when the voltage of said armature falls below the minimum, substantially as described.
7. An electric system comprising a working circuit, in combination with a storage battery, main and auxiliary direct current generators having a common armature shaft, the auxiliary armature being adapted to energize the field of the main generator and the armature of the main generator having two windings of unequal dimensions, suitable resistance connected with the larger armature winding, variable resistance connected in circuit with the field of the auxiliary generator and the smaller winding of the main armature, means also connected in circuit with said smaller winding for varying the resistance in the auxiliary field circuit and an automatic switch controlled by the latter means for connecting the battery with the working circuit also for disconnecting the same therefrom and connect the smaller and the larger windings of the main armature with the working circuit and the battery, respectively, substantially as described.

8. In an electric system of the class described, a working circuit, in combination with a storage battery, a direct current generator having a duplex armature, the windings of which are connected with said circuit and said battery respectively, a switch for disconnecting said armature windings from said circuit and battery and connecting said battery and circuit direct, means for energizing the field of said generator and for varying the strength thereof in response to the variations of potential upon said working circuit and electro magnetic means for actuating said switch when the potential of said duplex armature falls below or rises above a certain minimum voltage, substantially as and for the purpose specified.

9. An electric system of the class described, comprising a working circuit, in combination with a storage battery, a direct current generator having a duplex armature, whose windings are connected with said circuit and said battery respectively, charge controlling resistance interposed between said armature and said battery, an electro magnetic switch adapted to disconnect said duplex armature from said circuit and battery and connect the battery and circuit direct and vice versa, an auxiliary generator for energizing the field of said generator and itself energized by current from said working circuit and means also deriving current from said armature and controlling the action of said auxiliary generator.

10. An electric system of the class described, comprising a working circuit, in combination with a storage battery, a direct current generator having a duplex armature, a circuit for energizing the field of said generator, variable resistance controlling the latter circuit, circuits for connecting the windings of said duplex armature with said working circuit and said battery respectively, charge controlling resistance in the armature-battery circuit, an expansible conductor deriving current from one of the said armature windings, an electro magnetic switch for connecting said working circuit and said battery, and adapted to disconnect the same and connect said working circuit and battery with respective armature windings and means associated with said expansible conductor controlling said switch and said variable resistance, substantially as described.

11. In an electric system of the class described, a working circuit, in combination with a storage battery, a generator having a duplex direct current armature, a switch for connecting said battery and working circuit, or connecting said battery and working circuit to respective windings of said duplex armature, an auxiliary pole changing generator, having its armature on the shaft of the duplex armature and arranged to ener-

gize the field of the main generator, the auxiliary field circuit including variable resistance, and means energized from said duplex armature for varying said resistance, substantially as described.

12. In an electric system of the class described, a working circuit containing translating devices, in combination with a storage battery, a main generator having a duplex armature provided with windings for connection respectively with said working circuit and said storage battery, an electro-magnetic switch adapted to connect said circuit and battery with said duplex armature or to connect said battery and working circuit direct, a suitable pole changer for said generator comprising a second generator having an armature connected with the field circuit of said main generator and driven by said armature shaft, the field for said second generator being arranged in said working circuit, variable resistance device arranged in the field circuit of said second generator, a lever for actuating said variable resistance device, and an expansible conductor connected with said lever and receiving current from said duplex armature, substantially as and for the purpose described.

13. In an electric system of the class described, a working circuit, in combination with a storage battery, a generator having a suitable field and a duplex armature, the windings of which are adapted for connection with said working circuit and said battery respectively, an electro-magnetic switch governing the connection of the working circuit, battery, and armature, an auxiliary generator for energizing the field of said generator and having its own field energized by current from said armature, a variable resistance in the field circuit of the auxiliary generator and an expansible conductor in circuit with one of the windings of said armature for controlling said variable resistance and the action of said switch, substantially as described.

14. In an electric system of the class described, a working circuit, in combination with a storage battery, a direct current generator having a single field and a duplex armature, the windings of the latter being adapted for connection with said working circuit and said battery respectively, charge controlling resistance interposed between said battery and the respective armature winding, an electro magnetic switch adapted to connect said circuit and battery with said armature or said battery and circuit direct, a field energizing auxiliary generator having its armature driven with said duplex armature, the auxiliary generator field circuit, variable resistance therein, an expansible conductor connected with one of the windings of said duplex armature, and a supplementary switch actuated by said expansible

conductor for controlling said variable resistance and the action of the first mentioned switch, substantially as described.

15. In an electric system of the class described, a working circuit containing translating devices, in combination with a storage battery, a main generator having a duplex armature provided with windings for connection respectively with said working circuit and said battery; an electro-magnetic switch governing the connection of the working circuit, battery and armature, a second generator in the field circuit of said main generator and having a suitably energized field, variable resistance for controlling the strength of said field, and an expansible conductor in circuit with one of the windings of said duplex armature and operating said resistance, substantially as described.
16. In an electric system of the class described, a working circuit containing translating devices, in combination with a storage

battery, a main generator having a duplex armature provided with windings for connection with said working circuit and said battery respectively, an electro-magnetic switch governing the connection of said working circuit, battery and armature, a second generator for energizing the field of said main generator and having a suitable energized field, variable resistance for controlling the strength of said field, and an expansible conductor in circuit with one of the windings of said duplex armature and controlling said variable resistance and said switch, substantially as described.

In testimony whereof, I have hereunto set my hand, this 13th day of July, 1905, in the presence of two subscribing witnesses.

ALEXANDER McGARY.
